UNITED STATES PATENT OFFICE.

HANS H. WANDERS, OF BROOKLINE, MASSACHUSETTS, ASSIGNOR TO THE FLINTKOTE COMPANY, OF BOSTON, MASSACHUSETTS, A CORPORATION OF MASSACHUSETTS.

STACKING MACHINE.

Application filed April 23, 1920. Serial No. 277,153.

To all whom it may concern:

Be it known that I, HANS H. WANDERS, a citizen of Germany, residing at Brookline, in the county of Norfolk and State 5 of Massachusetts, have invented new and useful improvements in Stacking Machines, of which the following is a specification.

In the manufacture of such prepared roofing elements, as shingles or slabs, it is customary, after submitting the webs of felt to the usual saturating and coating instrumentalities, (by which the web is first impregnated with pitch, asphalt or other waterproofing material, coated with a high- 10 melting point pitch or asphalt and surfaced with a partially embedded layer of crushed slate or other mineral material), to pass the web progressively through machines which cut it into units, such as shingles or slabs or strips, each equal in length to the width of two or more shingles. Such machines operate at high speed and it has been the shop practice to employ a number of workmen stationed at the delivery 15 end of the machine to sort, count and stack the units.

The present invention has for its object to provide improvements in the mechanism for use in connection with the unit cutting machine for automatically stacking the units in groups with the same number of units in each group, so that they may be properly secured in packages for storage and shipment. In accordance with the present invention, 20 the stacking or grouping mechanism is coordinated with the cutting machine, so as to receive the units delivered thereby, and arrange them in groups or stacks. In connection therewith, a conveyer may be employed for delivering the groups at some other point where the stacks or groups may be bound with wire or otherwise packed.

In an application filed by Hildebrand and Wanders March 3, 1919, Serial No. 280,458, 25 there is set forth such a machine, and the present invention constitutes an improvement thereon and has for its object to improve the gate or switch shifting mechanism whereby the switch may be shifted with great rapidity and accuracy to form a new receptacle and release the stack of units contained in previously formed receptacles. Other objects of this invention will appear in the following description of the device, as 30 illustrated.

In the accompanying drawings.—

Figure 1 represents in side elevation, a machine for cutting sheets of roofing into small units, such as shingles or slabs, and a stacking mechanism cooperating therewith, which embodies the present invention. 60

Figure 2 is an end elevation of the stacking mechanism in connection with the conveyor.

Figure 3 shows the stacking mechanism 65 in side elevation.

Figure 4 shows an end view of the stacking mechanism, looking toward the cutting machine.

Figure 5 shows a longitudinal sectional 70 view of the stacking mechanism and cross section through the end of the conveyor, with the supporting frame of the stacker in elevation.

Figure 6 shows in side elevation the rear 75 end of the conveyor with respect to the stacker.

Figure 7 shows the far end of the conveyor or with the speed reducing mechanism.

Figure 8 is a section through the stacking mechanism operating gears showing the 80 relation of said gears.

Figure 9 is a more or less diagrammatic section through the stacking receptacles and the gate or switch that separates them. 85

Figure 10 is a view showing details of the switch shifting mechanism.

Figure 11 is a section on line 11—11 of Figure 10.

Figure 11^a is a detail view of one of the 90 sector shaped members showing certain details.

Figure 12 is a fragmentary sectional view on line 12—12 of Figure 10.

In explaining the principles of operation 95 of the instrumentalities, illustrated on the drawings, as constituting an embodiment of the invention, it should be understood that the invention is capable of various other embodiments, that the drawings are more 100 or less conventional and that the phraseology hereinafter contained is for the purpose of description and explanation, and not of limitation. One of the serious problems which must be solved in stacking roofing units in 105 evenly numbered piles or stacks, arises from the fact that the cutting machine operates continuously and at a relatively high speed, and also from the nature of the roofing units, which are usually surfaced with par- 11

tially embedded crushed slate or grit, and are therefore difficult to handle or manipulate. The severed units are continuously delivered in a constant stream from the cutting 5 machine, almost in contiguous end to end relation, and the mechanism for interrupting the stream and diverting a pre-determined number of units into one receptacle or holder, and the next succeeding predetermined number of units into another receptacle or holder, must operate evenly without 10 excessive jar and at a very high speed. In the machine which I shall hereinafter describe, I have presented a solution of the 15 problem which has proved to be satisfactory in commercial operation.

Another problem of material importance and one which the present invention attempts to solve, is the production of a gate 20 or switch operating mechanism which operates in such a manner that the stacking receptacles may be successively formed so quickly that the rapidly moving units may be directed into the proper receptacle and 25 when formed the stack may be released and a new receptacle formed almost instantaneously.

It is quite immaterial what particular form the cutting machine may take, so long 30 as it is capable of having the sheet of roofing fed thereto and of cutting it either into shingles or slabs. Any one of a number of cutting machines may be employed for this purpose.

35 The cutting machine, as conventionally shown, comprises a frame 15, which is supported some distance from the ground or floor upon a base 16, adapted to be adjusted as to position on the floor by means of castors 40 or rollers 17. At 18 are indicated cutters arranged longitudinally of the machine to cut or slit the web into a number of longitudinal strips or else form a series of longitudinal slots therein, (this depending on 45 whether the machine is for the purpose of producing individual shingles, or shingle strips or slabs), in the cutting operation the strips being advanced on the machine by means of feed rollers 19 or other suitable 50 means. At 20 there is indicated a chopping cutter adapted to cooperate with a stationary blade (not shown) by which the web is cut transversely so as either to sever the longitudinal strips into shingles of the desired 55 length or else to cut the sheets transversely in lines intersecting the slots, so as to produce serrated slabs or shingle strips. This machine is shown as simply one exemplification of shingle forming or slab forming 60 machines, which may be used in combination with instrumentalities embodying the present invention. As the units are cut from the web, they slide down a guide 21 and are delivered to an endless conveyor belt 22, the 65 upper stretch of which is preferably inclined

downwardly and outwardly so that the units carried thereby can be shot from the end of the conveyor into the stacking mechanism.

Any suitable power-transmitting mechanism may be employed for effecting the feed of the web and the operation of the various cutters. As shown on the drawings, power is transmitted to the cutting and stacking mechanism through the pulley 24 mounted 70 on shaft 23 and through a belt 25 trained about said pulley and connected with any suitable source of power (not shown). Power is transmitted from this main power shaft 23 to the cutting mechanism through 75 gear wheel 26 on shaft 23 which meshes with the large gear 27 on the chopping cutter shaft 28. From this shaft, the power is transmitted to the cutters 18 and to the feed rollers 19, through a chain of gears 29, 30, 80 31, 32 and 33, the first of which is in mesh with gear 34 on cutter shaft 28, which as above stated, is connected with the main source of power.

In order that the upper stretch of the conveyor 22 may be given the inclination, hereinbefore referred to, the belt is trained about rollers 35 and 36, the former on shaft 37 journaled in the frame of the cutting mechanism, is at a higher elevation than roller 36 95 which is located on shaft 38 journaled in brackets 39. These brackets are attached to the forward end of said frame, that is on the end toward the stacking mechanism. The conveyor is driven by means of a 100 sprocket wheel 40, on shaft 38 at the forward end of the belt, which is connected with sprocket wheel 41 mounted on the main power shaft 23 by means of a sprocket chain 42. The conveyor and the cutting 105 mechanism, both operate at a very high speed, the belt, however, moving more rapidly than the cutting mechanism, so as to receive the units delivered thereto and separate and space them from each other. The 110 reason for this will appear later.

The principle upon which the stacking mechanism operates will be understood from the diagrammatic illustration in Figure 9. Between two oppositely spaced walls 43 and 44 there is pivoted an inclined gate 45, having arms 46 and 47 extending upwardly and downwardly from its pivot point. Over or under this gate, as the case may be, the units are delivered from the conveyor. When the gate is in the full line position, the units pass over the top of the gate into the receptacle *a* temporarily formed by the lower arm or reach 47 of the gate contacting with the lower end of wall 43. When the predetermined number of units have been delivered into this receptacle, the gate is quickly shifted to the dotted line position, so as to bring the lower offset end of the gate into engagement with the wall 44, form- 120 125 130

ing temporarily a second receptacle or compartment *b* between the gate and the lower wall, into which a predetermined number of units are delivered until the gate shifts again to its full line position. As the gate swings from the full line to the dotted line position, the stack of units in the compartment *a* is delivered in upright position to the box conveyor 89 to be described. This conveyor 16 moves transversely of the longitudinal lines of the cutting and stacking machines, so as to carry the stacks of roofing units delivered thereto to one side or the other of the machine, where they may be deposited on a table 15 or manually removed therefrom and placed in a binding machine for binding each stack or pile of units with straps or wires. In the operation of stacking, it is very important that the gate should move very rapidly 20 from one position to another, and mechanism for this purpose will hereinafter be described. The reason for spacing the units on the conveyor to which they are delivered by the cutting machine, will now appear 25 since it is necessary that there be a sufficient interval between the successive arrival of units so as to allow time for the shifting of the upper end of gate or switch, and thereby prevent a unit from being gripped by the 30 arm 46 against one of the walls 43, 44.

Describing now in detail the stacking mechanism and having particular reference to Figures 1, 4 and 5, it will be seen that the two walls 43 and 44 are mounted in an inclined position toward the box conveyor at an angle to the horizontal equal to or greater than the angle of slip so that the units and stacks of units deposited therein will slide or tend to slide by gravity downward toward 40 and into the conveyor receptacles. These walls 43 and 44 are supported in said position by the supporting frame 49, and between the side walls 56 thereof which are connected by a plurality of cross bars, hereinafter described in connection with mechanism of the machine. The supporting frame is secured to a base frame 50 by means of bolts 51 or other suitable fastenings. This base frame comprises side members 52 secured together by rods 53. Sloping forwardly from the stacking mechanism and forming a substantial continuation of wall 44 and at approximately the same angle, is a chute member 57. This chute member is secured at the forward end of the stacking machine upon rods 55 supported on brackets 54 attached to the base frame 50 of the stacking mechanism. The member 57 is designed, in cooperation with a shield or baffle plate 109, (to be described), to direct the stacks of units to the box conveyor and has, on its upper face, angle bars 58 with upstanding flanges 59 placed in converging relation to each other and toward their lower ends to 65 form the guide-ways on the chute for more

accurately delivering the stack of units to the conveyor boxes.

It is desirable, on account of the heavy character of the material to be dealt with, to firmly brace the wall of the machine and 70 for this purpose the walls 43 and 44 are suitably reinforced by means of angle iron struts 60 and 61, and the member 57 is similarly braced by angle iron struts 62; and in order to absorb the shock caused by the gate 75 or switch 45, when the lower end thereof contacts with walls 43 and 44, as said gate is rocked suddenly about its pivot in forming the successive receptacles there is located on the lower end of the gate, a U-shaped member 80 85 63 having outstanding spring arms 64 which abut against buffer members 65 and 66 of rubber or other suitable material rigidly attached to transverse rods 65^a and 66^a of the frame by suitable clamps 67.

Between walls 43 and 44, and mounted to swing about gudgeons or trunnions 110 mounted in the frame walls 49 of the stacking machine is the gate 45, hereinbefore referred to. This gate is formed of two sheets 90 of metal 68 and 69 separated and braced by transverse bars 70. The upper sheet 68 of this gate extends forwardly and downwardly toward the box conveyor and has a chute 86 formed thereon by means of converging 95 angle iron members 87 located on its upper face, in a manner and for a purpose analogous to that of the chute shown at 57.

It is important that the units be delivered to the receptacles *a* and *b*, so as to be deposited one upon the other, and for this purpose there is secured at the upper end of wall 44, an angle member 72 forming a shoulder 73 and an upwardly inclined portion 74 against which the upper end of the 100 arm 46 of the gate abuts when receptacle *a* is being formed. This member 72 has suitable brace members 75, 76, and performs the important function of receiving certain of the units from the conveyor so that they 105 may be deposited one upon another in receptacle *b* when the switch is in proper position to form the said receptacle. On the upper arm 46 of the gate is a similar shoulder member 77 which performs a similar 110 function as to receptacle *a*. This last named shoulder member is angular and has its upper portion 78 lying at an acute angle to the sheet 69, and is braced by cross bars 79. In the apex of the angle between members 115 68 and 69 is located a crossbar 80 triangular in cross section for the purpose of bracing these members and securing them together. On the lower side of wall 43 and on the lower side of the gate 45 are attached pairs of 120 125 downwardly extending members 81 and 82 which form the sides of receptacles *a* and *b* and are designed to hold the units in position when being stacked.

The lower end of wall 43 is bent down- 120

wardly at an angle as at 182 so as to make contact with the upper side of the gate when the latter is in position to form receptacle *a*; this downwardly bent portion being designed to form the lower end wall of said receptacle and in a similar manner the lower sheet-metal member 69 of the gate is bent downwardly at an angle to form the lower end wall 183 of the receptacle *b* when the gate is in proper position. For purposes of stability, wall 182 is suitably braced at 84 and the end wall 183 is braced by angle member 83 placed between the wall and an offset portion 48 of the gate, extending from the sheet 68 which is in turn supported by the brace members 85.

The stacks or bundles of elements are delivered alternately from the receptacles *b* and *a* over the chutes 57 and 86 into the U-shaped boxes 88 of an endless conveyor 89 and are carried therein to a suitable place of deposit where they are taken from the boxes and made into bundles in a manner, as hereinbefore indicated. The endless chain conveyor 89 carrying boxes 88 are trained about sprocket wheels 90, 91 suitably supported.

It will be readily understood that the endless conveyor 89 is subjected to heavy loads when in operation and for this reason, has a tendency to sag. To avoid this the sprockets 90 are mounted for sliding adjustment on the base member 191 and are adjusted thereon by means of the feed screw 192 operated by handle 193, to increase the tension of the conveyor chains.

It is desirable that the boxes move with sufficient speed that one box, when it has received its stack, shall be advanced far enough to be out of the way and for another to have been advanced to position to receive the next succeeding stack as it is delivered from the stacking machine. While speed is not necessary, a considerable amount of power is desirable inasmuch as the load to be carried is very heavy, and for this reason there is located at the opposite end of the chain from that at which the tension adjusting mechanism is located, a power device 194 of any desirable character, such as a motor or the like, and to which the sprockets 91 are connected through a chain of reducing gears 93, 94, 95 and 96, meshing with gear 97 attached to the shaft 98 of the sprockets, and the gear 93 meshing with pinion 92 on the power shaft. This pulley and the chain of gears are mounted for support on a suitable frame 194.

In order to support the conveyor 89 which is comprised of sprocket chains 101 connected by cross bars 102, sprocket wheels 90, 91 are attached to the shafts 98, 100; said sprockets having their teeth in mesh with the sprocket chain. The conveyor is supported at its side edges by means of rollers

103, see Figure 5, attached to the cross bars 102 and which travel in tracks or guideways 104 arranged longitudinally of the line of travel of the belt. An additional support for the belt 105 is located centrally of the conveyor on its line of travel and placed above the track or guideways 104 is a shield or protector member 103, for protecting the track against foreign matter, such as grit, slate and the like, which might otherwise drop thereupon. The tracks or guideways are supported in elevated position above the ground at intervals, along their course by means of supporting members 107. Mounted upon a plurality of these supports 107 are struts 108 to which the shield or baffle 109, hereinbefore mentioned, is attached.

As has been stated above, the rapid switching of the gate from one position to another is of the utmost importance and it is desirable that suitable mechanism for accomplishing this, should be provided. Such mechanism has been provided and will now be described. The gate 45 is pivotally mounted on trunnions or gudgeons 110, as mentioned above, journaled in the frame of the stacking mechanism, and this gate is connected with the cutting mechanism in such a manner that when a certain number of units have passed through the cutter and over the endless belt into the receptacle *a* or *b*, as the case may be, the gate will automatically turn on its pivot thereby releasing the stack in one receptacle and forming another receptacle. Inasmuch as the units are being shot into the stacker very rapidly, this action must take place with the least possible delay and the new receptacle must be formed in the interval between the delivery of two roofing units. To effect this very rapid movement and to determine the same by the number of units cut, the mechanism is controlled and timed through the medium of the sprocket wheel 111, attached to the cutter shaft 28, and 112 which is connected with sprocket wheel 112 on shaft 113, journaled in the stacking frame, by means of sprocket chain 114. By a train of reducing gearing, a gear 115 is slowly rotated. This train may include sprocket 116 on shaft 113, a chain 116, a sprocket 117 on shaft 119, and a pinion 118 on shaft 119 intermeshing with gear 115, (see Figure 8). The operation of the gate is regulated by the cutting machine, but by the substitution of change gears or sprockets in the train, it may be timed so that any predetermined number of units will be deposited in each receptacle before the operation which shifts the gate takes place. In order that the gate may be held stationary when the machine is being repaired, or when desirable for any other reason, there is located adjacent gear-wheel 115, a lock mechanism 120, which comprises a plug 121

seated in the bore 122 of a sleeve 123 adjustably mounted in the frame 49 of the stacking mechanism. This plug is spring-pressed outwardly and is adapted to engage an aperture in gear 115, whereby wheel 115 may be held stationary and the sleeve 123 is screw-threaded to receive an internally screw-threaded cap 125 thereupon, and seated in the bore of the sleeve with one end abutting against said cap and the other end against the rear end of the plug 121 is a spring 126 by means of which the plug is pressed outwardly. The plug has extending therefrom a pin 127 riding in slot 128 and this slot has an offset notch 129 into which the pin may be rotated to hold the plug 121 retracted. This plug, of course, is brought into play in connection with the gear only when the machine is at rest.

20 Proceeding now to describe in detail the mechanism for shifting the gate or switch;—there is located on the gear 115 a pin 130 and attached by suitable means (hereinafter to be described) to the switch or gate 45 is a tubular member 131 having a longitudinal slot 132 communicating with the bore thereof. Within the member 131 and mounted to reciprocate therein is a plunger 133 apertured to receive the end of the pin 130 projecting through said slot. Seated in both ends of the tubular member 131 and abutting at their far ends against the caps 134 which are attached to the ends of the member and at their near ends against the ends of the plunger 133, are compression springs 135 and 136. These springs are adapted to be compressed by the plunger 133 at different phases of the revolution of gear 115, owing to mechanism whereby the tubular member is held against rectilinear movement as will hereinafter appear, and when they are released the tube will be actuated longitudinally by the force stored in the spring thereby shifting the position of the switch. Inasmuch as the tubular member plays an important part in shifting the gate, it may properly be termed the gate shifting member, and is adapted, when shifting the switch, to have a rectilinear movement.

50 If unrestrained, the point of contact of the tubular member with the pin on the gear 115 would be carried thereby in a circular path and the force exerted on the tubular member by the pin on the gear, at any moment in its revolution, may be resolved into two components, one tending to move the tube laterally or horizontally and the other vertically, and when the tube is prevented from moving in one of these directions will tend to move in the other. When the tube is limited in its vertical movement, the pin 130 and plunger 133, still having movement along its vertical component, will, as stated above, compress one of the springs, storing energy therein, which at the proper time,

that is when the restraining machine is rendered ineffective, will shoot the tube in a vertical direction thereby quickly shifting the gate as will be hereinafter set forth.

In order to prevent the shifting movement of the tubular member until a predetermined number of units are deposited in the receptacle *a* or *b* as the case may be, there is mounted on the frame 49 of the stack mechanism, below the gear 115, inner and outer 75 arcuate stop members 137 and 138 spaced apart by spacer blocks 139 placed between them at their ends. The inner member 137 is provided on its upper and lower edges with guideways 140 and 141 formed thereon, 80 for a purpose to be described. On the diagonally opposite ends of these guideways are tripping members 142 and 143, mounted for adjustment longitudinally of the guideway and having elongated slots 144 therein, 85 through which extend set screws 145 by means of which said tripping members are adjustably fastened to said guideways. The faces of the tripping members towards the line of travel are bevelled at 146 so that when 90 a member which is mounted on the plunger 133 and travels on the guideway (as will be described), comes in contact therewith, the member will be forced off the guideways and permit the vertical movement of the tubular 95 member and the operation of the gate.

The tubular member 131 is connected with the gate 45 by means of the following mechanism. Adjustably mounted on the upper portion of the tubular member 131, and at a point intermediate the gear 115 and its upper end there is a two part collar 147 held in place by means of clamp bolts 148. Extending from opposite sides of this collar are trunnions 149 extending into bearings 150 105 on the ends of arms 151, which are rigidly secured on a shaft 152, (see Figure 4). Rigidly secured to shaft 152 to rotate therewith are other arms 154 on either side of the stacking mechanism. Pivoted to these arms, 110 by pivots 155, are downwardly extending bars 156 which are pivotally attached at their lower ends to the switch for moving it from one position to another for the purposes stated.

115 The construction of the trip member in relation to the related parts is in detail as follows: The trip member or plug 157 is mounted in an aperture 158 in the block 159 which is secured to the cylinder 131 by 120 means of clamping members 160 drawn together in clamping position on the tube by means of screw bolts 161. Mounted in the aperture and surrounding the plug 157 is a sleeve 162 of metal or other suitable material. This sleeve is reduced toward one end to form a shoulder 163 adapted to abut against a similar shoulder on the plug to limit its outward movement. Screw-threaded into the opposite end of the sleeve is a cap 130

164 having a projection thereon about which is seated a compression spring 165, the other end of the spring being seated in an aperture 166 in the unreduced portion of the plug and 5 tending to press the plug outwardly to a position to ride in the guideways 140, 141.

It is now obvious from the above construction that the plug or trip member 157 riding in the guideways 140, 141, will be pressed inwardly against the pressure of springs 165 when said plug comes in contact with the bevelled face of either the tripping members 142, 143 and the tubular member 131 will thereby be freed or released to move in a 15 vertical direction up or down, as the case may be.

In operation, the web of roofing is fed continuously by the usual feed rolls 19, through the unit forming machine, and is 20 formed into units of the desired character. The severed units are received by the conveyor 22, which constitutes an intermediate feeding mechanism, which, travelling at a higher rate of speed than the sheet of roofing, 25 spaces the units apart in the direction of their travel so that there is an appreciable interval between the rear edge of the next one succeeding it. Assuming that the gate is in the position, (shown in Figure 5), the 30 units pass over the inclined end of the gate and drop onto the lower end of the gate, with their flat sides resting on said gate,—their further progress being stopped when they abut against the almost vertical portion of the plate 182. Each unit passes over the preceding unit and a pile or stack is 35 gradually formed, until a predetermined number have been stacked. A similar operation takes place with respect to the lower 40 wall when the gate is in position to form a receptacle therewith. During this time, through the speed reducing gearing, the gear 115, with pin 130 riding in slot 182, is caused slowly to rotate, as hereinbefore described, and as it turns from the position, 45 shown in Figures 8 and 10 of the drawings, its first tendency is to move the lower reach of the cylindrical member to the right and to carry the plunger 133 downwardly compressing spring 136, the downward movement 50 of the tube being prevented however, by the engagement of stud 157 with the arcuate guide 137. When the gear has made approximately one quarter revolution, the 55 lower reach of the cylindrical member 131 moves toward the left until approximately another quarter revolution is made, the plunger 133 still descending and further compressing the spring. At about this point 60 the plug or trip member 157 comes into contact with the bevelled face of tripping member 142 whereupon the trip member is pressed inwardly against the pressure of spring 166 and the cylindrical member 131 65 released and is shot suddenly downwardly

by the force of the compressed spring 136. The force thus stored in the spring is sufficient to project the block 159 beyond the lower edge of the arcuate members where the plug or trip member 157 is free to resume its 70 normal position, and thus takes under the guide.

It is obvious that as the cylindrical member is shot downward that the gate is quickly shifted, and the mechanism then passes 75 through the latter, half of its cycle at the end of which the gate is again shifted. In this latter half of the cycle, the gate is in contact as hereinbefore set forth, with the lower wall and the operation is similar to 80 that just described and is in detail as follows; The protruding end of the plug or trip member 157 rides on the guideway 141 toward the left, for approximately a quarter revolution of the gear 115; compressing 85 spring 135, and then toward the right until a point near the starting point is reached by the pin 130 when the plug 157 will again be forced inwardly by tripping member 143 and the cylindrical member shot upwardly 90 by the force in the compressed spring 135, again operating the gate to release a stack, of units and form compartment *a*, so that for every half revolution of the gear 115 there is a stack of units released and deposited 95 in the box 88 of the conveyor and a new compartment or receptacle is formed.

As the switch operates, in the manner thus described, the stacks or bundles of units formed in the receptacles are delivered to 100 the boxes of the conveyor whereby they are carried along its course by said conveyor and are lifted therefrom by workmen and formed into bundles by being tied or otherwise fastened together either by a machine or by hand. Due to the relation of parts of the machine, the stacks are delivered to the boxes so that the units thereof rest on one edge and in upright position, making it easier to handle the bundles 110 when removed from the receptacles.

In considering the instrumentality which I have termed the gate, it will be seen that it performs two different functions, which if desired could be performed by two different 115 instrumentalities. That is, the upper end of the gate performs the function of a switch for directing the flow of units from the forming or cutting machine, automatically and alternately into separate paths. 120 The lower end of the gate serves the function of arresting the flow of diverted units until a pile or stack thereof is formed. As I have said, these elements, for the sake of simplicity of construction in the present 125 embodiment of the invention, are formed together in a single element or instrumentality since the same operating mechanism may be employed for actuating the switch and the arrestor.

It will be seen from the foregoing specification that I have produced a machine by which units, difficult to manipulate, are cut into shape, mechanically stacked for handling or packaging and are conveyed to a suitable place where this can be done.

Having thus explained the nature of my said invention and described a way of making and using the same, although without attempting to set forth all of the forms in which it may be made or all of the modes of its use, what I claim is:

1. In a stacking mechanism, a frame therefor, a gate pivoted on said frame and mechanism connected with said gate to shift the position thereof, said means comprising a tubular member having a spring seated therein, a gear on said frame adapted when rotated to compress said spring, a guideway on said frame, a stop on said tubular member adapted to ride on the guideway, and tripping means on said guideway whereby when the stop comes in contact therewith, the tubular member will be freed to move downward under force of said spring and the position of the gate will be shifted.

2. In a stacking mechanism, a frame therefor, a gate pivoted on said frame, a hollow member connected with said gate to shift the position thereof, a spring in said member, means for compressing said spring whereby its force will tend to move said member longitudinally, a stop on said shifting member, a guide contacting with said stop for arresting the longitudinal movement of said shifting member, and tripping means for releasing the stop whereby rectilinear movement of the shifting member by said spring is permitted and the gate is shifted.

3. In a stacking mechanism, a frame therefor, a gate pivoted in said frame, chambered shifting means connected with said gate to shift the position thereof, a resilient member in said chamber, means for compressing said resilient member, trip mechanism for arresting the shifting movement of said shifting means under force of said resilient member, and means for tripping said limiting means to permit shifting movement.

4. In a stacking mechanism, a frame therefor, an oscillatory gate pivoted in said frame, shifting means connected with said gate to shift the gate back and forth into two alternate positions, a resilient member, means to compress said resilient member, said resilient member tending, when compressed, to cause the shifting means to move so as to shift said gate, a stop to limit said movement and means for tripping said stop whereby shifting movement is permitted.

5. In a stacking mechanism, a frame therefor, a gate pivoted in said frame, shift-

ing means connected with said gate to oscillate the same into two alternate positions, said means having a plurality of resilient members associated therewith in such manner that when said resilient members are compressed they will tend to cause shifting movement of said shifting means, a stop and a co-operating guide on said frame to limit said movement, and means for releasing said stop whereby said movement may take place and the gate be shifted.

6. In a stacking mechanism, a frame therefor, a gate pivoted in said frame, a tubular member connected with said gate and containing a spring in such manner that when said spring is compressed it will tend to cause a longitudinal movement of said member, a stop on said member, a plunger in said member, to compress said spring, a gear connected to said plunger, a stationary guide on this frame, and coacting with said stop to arrest the movement of said member, and tripping means for releasing said stop from said guide, whereby said member may be actuated by said spring to shift the gate.

7. In a stacking machine, a frame therefor, a gate pivoted in said frame and adapted to contact at one end with the parts of the frame to form receptacles therewith, means to shift the gate from one receptacle forming position to the other, and means on said gate adapted to absorb the shock when the gate is shifted.

8. In a stacking machine, a frame therefor, a gate pivoted in said frame and adapted to be shifted so that the lower end thereof contacts with the frame to form receptacles when the gate is in proper position, and means to shift the gate from one receptacle forming position to another and co-operating means on the frame and on the gate arranged to absorb the shock when the gate is shifted.

9. In a stacking machine, a frame therefor, a gate pivoted in said frame and adapted to be shifted so that its lower end thereof contacts with the frame, to form receptacles when the gate is in proper position, means to shift the gate from one receptacle-forming position to another, a U shaped member on the frame, and means on the gate co-operating therewith to absorb the shock when the gate is shifted.

10. A stacking machine comprising a frame having a chute, a movable gate therein and adapted to engage the opposite walls thereof alternately to form receptacles, and mechanism to shift said gate, said mechanism including an arcuate guide on said frame, a rotary member having a crank pin, a tube operatively connected to said gate, springs in said tube, a plunger between said springs and connected to said crank pin, a stop on said member to ride against said

guide and tripping devices arranged to release said stop from the guide when one or the other of said springs has been compressed by the plunger.

5 11. A stacking machine comprising a frame having a chute, a movable gate therein and adapted to engage the opposite walls thereof alternately to form receptacles, and mechanism to shift said gate, said mechanism including an arm connected to said gate, a tube pivoted to said arm, a plunger in said tube, springs in said tube between said plunger and the ends of said tube, a rotary member having a crank pin engaging said plunger to store power in said springs alternately, means for arresting the movement of said tube by said springs, and devices for automatically arresting and releasing said tubes.

10 12. A stacking machine comprising a frame having a chute, a movable gate therein and adapted to engage the opposite walls thereof alternately to form receptacles, an arm connected to said gate, and mechanism to shift said gate, said mechanism including a swinging member pivotally hung on said

arm, a stationary guide for guiding the swinging movement of said member, opposing springs connected to said arm and arranged to have power stored therein to move 30 said arm longitudinally, rotary means for storing power in said springs and swinging said member and means for automatically arresting said member against longitudinal movement and automatically releasing said 35 arm.

13. A stacking machine comprising a frame having opposing walls, a gate pivoted between said walls to form alternately therewith a stacking receptacle, a rock shaft 40 pivotally connected to said gate to move it from one receptacle-forming position to another, an arm on said rock shaft, a member hung on said arm, springs connected to said arm and adapted when power is stored 45 therein to move said member and arm, and thereby rock said shaft, means for storing power in said springs, and means for automatically arresting and releasing said arm.

In testimony whereof I have affixed my 50 signature.

HANS H. WANDERS.
